(57) **CLAIM**

The ornamental design for a visor organizer, as shown and described.

DESCRIPTION

FIG. 1 is an isometric view of the visor organizer showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

FIG. 1 depicts dashed lines across the top of the visor organizer. These dashed lines are presented in the drawing for illustration only, and do not form a part of the claimed design.

The Visor Organizer is shown on an enlarged scale in FIGS. 6 and 7 as compared with FIGS. 1-5.
